[57] ABSTRACT

In a transistor radio receiver, two time constant resistors, one of which is a variable resistor, are connected in series via a signal detection circuit to a power source and a time constant capacitor is connected to the junction point of the two resistors to form therewith an automatic gain control voltage generating circuit, and a squelch transistor whose base is connected to the movable terminal of a potentiometer, so that the squelch transistor which is normally biased to be conductive is quickly cut-off in response to even a weak signal input to the receiver.

TRANSISTOR RADIO RECEIVER EMPLOYING AN IMPROVED SQUELCH CIRCUIT

The present invention relates to a transistor radio receiver provided with an improved squelch circuit.

As is generally known, a squelch circuit serves to suppress the output of the audio amplifying stage when no signal is received, and to permit said stage to operate normally at the time of a signal input, in order to prevent the amplification and output of useless noise which increases at the time of a non-signal input.

Such squelch circuits have been proposed in various ways but the construction of these circuits is complicated, and they generally suffer from a lack of sensitivity at low signal levels. For example, if there is a small or weak voice signal input having power less than a certain value, the conventional squelch circuit will generally not recognize this signal, and accordingly will continue to perform its squelch function with the result that the voice signal is not amplified, but is cut off as if it were a noise at the time of a non-signal input.

An object of the present invention is to provide an improved squelch circuit which is much more sensitive at low signal levels.

Another object of the present invention is to provide an improved squelch circuit which is capable of releasing its squelch function in response to receipt of even a very weak signal input.

A further object of the present invention is to provide an improved squelch circuit which is relatively simple in construction and therefore simple and economical to manufacture.

Generally a radio receiver includes a high frequency signal amplifying circuit stage for amplifying a high frequency carrier wave, on which is superimposed an audio frequency signal to be detected, a converter for converting the carrier wave into an intermediate frequency signal, an intermediate frequency signal amplifying circuit stage, a detector or signal detection circuit stage for separating the audio frequency signal from the carrier, and an audio frequency signal amplifying circuit stage. In such a receiver, it has been noted that the audio frequency signal which is detected by the detection circuit in response to application of an input signal to the receiver is changed to a significant extent upon receipt of a very weak signal input, as compared to the non-signal condition. In accordance with the present invention, this voltage change which is produced by receipt of a signal input is utilized to control the action of the squelch circuit.

The signal detection circuit of a standard radio receiver consists of a diode coupled to an intermediate frequency transformer, and the combination of a resistor and a capacitor connected to the diode. This circuit generates a negative D.C. output voltage, at the time of a non-signal condition, corresponding to the voltage drop (usually about 0.1V) across the diode with the same polarity referenced to ground, while a positive D.C. output voltage is generated when an input is applied to the receiver. As a result, there is generated in such a circuit an output voltage having a polarity which can be used to erase the output voltage from the audio amplifier at the time of a non-signal condition. Therefore, in accordance with the invention the output voltage from the signal detection circuit at the time of this non-signal input is used to generate a bias voltage;

the squelch circuit is biased with this bias voltage; and, since the polarity of the bias voltage changes upon receipt of an input to the receiver, the bias voltage performs the squelch action on said squelch circuit only at the time an output voltage value is generated from the audio amplifier during a non-signal input condition.

These and other objects, features and advantages of the present invention will become more apparent from the following detailed description thereof, when taken in conjunction with the accompanying drawings which illustrate two embodiments of the present invention, and wherein:

FIGS. 1 and 2 are schematic circuit diagrams of a transistor receiver to which is applied the squelch circuit according to the present invention.

FIGS. 3 to 5 are equivalent circuit diagrams illustrating the operating principles of the present invention.

Referring first to FIG. 1, stage 1 is an intermediate frequency amplifier circuit, the amplification factor of which is changed by an automatic gain control voltage (AGC) applied to the input thereof. The next stage 2 is a second intermediate frequency amplifier circuit coupled to the circuit in stage 1. To the base of a transistor 20 TR₁ of the first stage intermediate frequency amplifier circuit 1, there is supplied for amplification an input signal converted to an intermediate frequency by a frequency converting circuit (not shown) through a transformer T₀. The output of the transistor TR₁ is supplied for amplification to a transistor TR₂ of the second stage intermediate frequency circuit 2 through transformer T₁, and the output of the transistor TR₂ is supplied to a detection diode D in a detection circuit 3 via transformer T₂.

35 The detection output of the diode D is applied for rectification to a parallel circuit consisting of a capacitor C₁ and a resistor R₁, and the detected output is also supplied to a time constant circuit 4 in which the voltage is divided by the potentiometer VR₁ and a resistor R₂, so that the AGC voltage V_{AGC} is obtained across the capacitor C₂. Further the end B of the transformer T₂ is connected to a negative terminal of the power source E.

An audio frequency output detected by the diode D after being rectified by the resistor R₁ and capacitor C₁, is supplied for amplification to a transistor TR₃ in the audio frequency amplifier circuit 5, and the amplified output thereof is supplied to a following audio frequency amplifier circuit (not shown) from the output terminal 6. The negative terminal of power source E is connected through the voltage dividing combination of resistors R₆ and R₇ to bias the base of transistor TR₃.

55 A squelch circuit 7 according to the present invention includes a transistor TR₄ having its collector connected to the emitter of the transistor TR₃ of the audio frequency amplifier circuit 5, the base of transistor TR₃ being connected to the movable contact of the potentiometer VR₁ of the time constant circuit 4 through the resistor R₅, and the emitter being connected to the negative terminal of the power source E. The transistor TR₃ for amplifying the audio frequency signal is a PNP-type germanium transistor and the emitter is grounded through the parallel circuit of the resistor R₃ and the capacitor C₃. As for the other transistors TR₁, TR₂ and TR₄, an NPN-type silicon transistor is used. The positive terminal of the power source E is grounded. The

AGC voltage is supplied to the base of the transistor TR_1 of the first stage intermediate frequency amplifier circuit 1 through the resistor R_4 and the secondary coil of the transformer T_0 . The other circuit constructions exclusive of the squelch circuit are well known, so that their operation should be understood without further explanation.

The present invention is characterized in that the potentiometer VR_1 is used as a resistance in the time constant circuit 4 and a squelch ON-OFF voltage for control of the squelch transistor TR_4 is provided by adjusting the movable contact of the potentiometer VR_1 to provide a proper bias for the squelch transistor. Accordingly, the circuit construction of the invention is quite simple and the ON-OFF control of the squelch operation is very sensitive.

The advantageous features of the present invention will become more clear from the following detailed explanation of the operation of the circuit of FIG. 1. When the transistor TR_1 is receiving no signal, no signal will be applied to the detection circuit 3, so that as shown in FIG. 3, the diode D is biased conductive by the electric power source E through the resistor R_2 , the variable resistor VR_1 of the time constant circuit 4 and the secondary coil of the transformer T_2 . Therefore, the capacitor C_1 will be positively charged with reference to the negative terminal of the power source E (shown by $\oplus$ and $\ominus$ in the figures) to a voltage corresponding to the voltage drop (about 0.1 V) across the diode in its conducting state, thereby providing the voltage V_D . However, the capacitor C_2 is negatively charged with reference to ground (shown by $\oplus$ and $\ominus$ in the figure) to a voltage corresponding to the voltage drop across the resistor R_2 ; therefore, the AGC voltage V_{AGC} is positively provided with reference to the negative terminal of the power source E.

The positive AGC voltage V_{AGC} referenced to the negative terminal of the power source E is obtained by subtraction of the voltage across the capacitor C_2 from the voltage V_E of the power source, so that when this voltage V_{AGC} is supplied to the transistor TR_1 , it becomes a forward bias. A base current therefore flows by means of this forward bias into the resistor R_1 and the transistor or transistors (shown in dotted line) are also supplied with this AGC voltage. The total amount of the respective base currents flowing through the transistors is designated i , while the current flowing through the variable resistors VR_1 is designated i_D . These currents i and i_D in combination flow through the resistor R_2 .

By observing from the point A to the right in FIG. 3, the circuit 8 including the transistor TR_1 and subsequent transistors receive the AGC voltage. Assuming now an equivalent resistance for the circuit 8 of R_a , a resistance value for the potentiometer VR_1 of R_b and a resistance value for the resistor R_2 of R_c , then the AGC voltage is expressed by the following equation:

$$V_{AGC} = \frac{V_E}{1 + \frac{R_c}{R_b} + \frac{R_c}{R_a}} + \frac{V_D}{1 + \frac{R_b}{R_c} + \frac{R_b}{R_a}} \quad (1)$$

If a signal input is supplied to the transistor TR_1 , the diode D performs a well-known detection function, and the detection output is applied to the capacitor C_1 . This detection output charges the capacitor C_1 this time in

the negative direction (as shown by $(-)$ and $(+)$ in FIG. 3) with respect to the negative terminal of the power source and this charge across the capacitor C_1 increases with the increase of the applied input signal, so that it produces an inversion in the polarity of the voltage V_D across the capacitor. Accordingly, V_{AGC} decreases.

When $R_b = 20 \text{ k}\Omega$, $R_c = 56 \text{ k}\Omega$ and $V_E = 9 \text{ V}$, and the values of $R_a = 100 \text{ k}\Omega$ and $50 \text{ k}\Omega$, respectively, the values of the V_{AGC} , which decreases in response to decrease in the voltage V_D caused by the increase of the input signal, as calculated by the Equation (1) are as follows:

	V_D	$V_{AGC} (R_a = 100 \text{ k}\Omega)$	$V_{AGC} (R_a = 50 \text{ k}\Omega)$
10	+0.1 V	+2.124 V	+2.0 V
0	+2.06	+1.95	
-0.5	+1.739	+1.665	
-1.0	+1.417	+1.38	
-2.0	+0.775	+0.81	
-3.0	+0.13	+0.24	
-4.0	-0.51	-0.33	

As described above, the present invention is designed to sensitively actuate the squelch transistor TR_4 in response to slight changes of the AGC voltage, which in turn is responsive to the amplitude of the input signal. Such control is attained by connecting the base of the transistor TR_4 through the resistor R_3 to the movable contact of the potentiometer VR_1 of the AGC time constant circuit 4, while the emitter of the transistor is connected to the negative terminal of the power source E.

As the squelch transistor TR_4 , a Hitachi silicon NPN-type transistor 2SC 458 is preferably used. Its conductive threshold voltage is 0.6 V, so that the circuit is adjusted to provide 0.6 V (preferably 0.68 V) as a bias voltage V_{eb4} between the emitter and the base of the transistor TR_4 at the time of non-signal input. This critical bias is obtained by adjusting the movable contact of the potentiometer VR_1 .

Supposing that the equivalent resistance value R_a of the circuit 8 in FIG. 3 is $100 \text{ k}\Omega$, as shown in the figure, a detection circuit output voltage V_D equal to 0.1 V with reference to the negative terminal of the power source will be generated in the capacitor C_1 and the AGC voltage V_{AGC} of 2.124 V including the voltage V_D will be generated at the point A with reference to the negative terminal of the power source E with no signal input to the receiver. In order to keep the squelch transistor TR_4 in the conductive state at the time of non-signal input, a bias voltage V_{eb4} of 0.6 V has to be provided from the AGC voltage between the emitter and the base of the transistor TR_4 . Thus, the movable contact of the potentiometer VR_1 must be so adjusted that the resistance value R_b' of the portion of the potentiometer between the end connected to the diode D and the movable terminal becomes $4.93 \text{ k}\Omega$, in the case where the resistance R_b of the potentiometer VR_1 is $20 \text{ k}\Omega$.

Once the movable contact of the potentiometer VR_1 is adjusted as required, the transistor TR_4 is rendered conductive providing a large collector current which flows through the resistor R_3 ; thus, a large voltage drop is provided thereacross. Thus, a large negative emitter bias voltage V_{es} is provided at the emitter of the audio frequency amplifying transistor TR_3 with respect to

ground. On the other hand, to the base of the transistor TR_3 , there is provided a bias voltage V_{b3} , derived from division of power source voltage V_E by the resistors R_6 and R_7 . The resistors R_3 , R_6 and R_7 have a value which provides an emitter bias voltage V_{eb3} to the emitter of the transistor TR_3 which becomes larger than the base bias voltage V_{b3} in the negative direction with reference to ground when the squelch transistor TR_4 is rendered conductive by the non-signal input condition, and becomes smaller than the base bias voltage when the squelch transistor TR_4 is interrupted by a weak signal input. Accordingly, at the time of a non-signal input, the transistor TR_3 is rendered non-conductive and the squelch action becomes effective.

Next, the change in the squelch action will be explained for the condition wherein an input signal is supplied to the first stage transistor TR_1 from the transformer T_0 to reduce the output voltage V_D of the detection circuit from 0.1 V to 0 V. Although the amount of change in V_D is 0.1 V, it is apparent from the foregoing table that the AGC voltage V_{AGC} only changes from 2.124 to 2.06 V. However, the bias voltage V_{eb4} between the emitter and the base of the squelch transistor TR_4 is made up of the output voltage V_D of the detection circuit added to the voltage drop due to the part R_b' of the resistance value R_b in the potentiometer VR_1 . Therefore, the equivalent circuit at the time of the above-described signal input is as shown in FIG. 5. Under these conditions, V_{eb4} becomes 0.507 V, which is the proportion of V_{AGC} across the resistance portion R_b' . This means that a change in V_D by 0.1 V causes a change in V_{eb4} of 0.093 V, reducing the bias of transistor TR_4 to a value below its cut-off.

Accordingly, the squelch transistor TR_4 is immediately cut off to reduce the voltage drop across the resistor R_3 , and the audio frequency signal amplifying transistor TR_3 once again operates under normal conditions. Therefore, according to the present invention, even if a small change of about 0.1 V occurs in the output voltage of the detection circuit by the arrival of a small signal input to the receiver, the squelch circuit 7 is cut off, so as to permit normal operation of the audio frequency amplifier circuit.

The strength of the input signal sufficient to provide the necessary change of about 0.1 V in the detection output may be small depending upon the design of the preceding circuit.

For the transistor TR_3 in the above-described embodiment, the Hitachi germanium PNP-type transistor 2SB-75 was used. In order to switch this transistor from the conductive state to the cut-off state, it is easier to change the emitter potential to be more negative than the base potential by causing a current to flow to the emitter resistor R_3 , as described above, than to change the potential of the base of the transistor. However, a silicon NPN-type transistor 2SC 458 can also be used as a transistor TR_3 . In such a case, transistors TR_1 through TR_4 can be made up of the same conductivity type transistors.

The transistor 2SC 458 has, as described above, a very sharp cut-off characteristic for the collector current with variation of base bias voltage, so that a large conductive collector current from the squelch transistor TR_4 is caused to flow to a part of the bias controlling resistor R_6 for the audio frequency signal

amplifying transistor TR_3 , and the base bias voltage of the transistor TR_3 is made to be close to ground potential, so as to keep the transistor TR_3 in a cut-off state.

A second embodiment of the present invention is illustrated in FIG. 2. The circuit of this embodiment has the negative terminal of the power source E grounded, but is basically the same as the circuit of FIG. 1. Therefore, similar elements in the respective circuits have been indicated by corresponding reference numerals.

As is apparent from FIG. 2, in the second embodiment of the present invention, the bleeder resistor R_6 is made up of two resistors R'_6 and R''_6 , which resistors are connected in series with the resistor R_7 to the power source E, point of connection X of the resistors R'_6 and R''_6 being connected to the collector of the squelch transistor TR_4 and the point of connection Y of the resistors R''_6 and R_7 being connected to the base of the NPN-type transistor TR'_3 for amplifying the audio frequency signal.

When the squelch transistor TR_4 is conducting, the resistance between the emitter and the collector at that time becomes quite small, and thus the potential of the point X is lowered. Accordingly, the base bias voltage of the transistor TR'_3 obtained by dividing the potential between the resistors R''_6 and R_7 is also lowered. Therefore, the values of the resistors R'_6 , R''_6 and R_7 , are, respectively, so selected that the base bias voltage of the transistor TR'_3 becomes lower than the cut-off voltage thereof at the time of conducting of the transistor TR_4 and higher than the cut-off voltage at the time that the transistor TR_4 is cut off. Therefore, the squelch circuit is turned on at the time of non-signal input and is turned off at the time of signal input.

While we have shown and described two embodiments in accordance with the present invention, it is understood that the same is not limited thereto but is susceptible of numerous changes and modifications as known to a person skilled in the art, and we therefore do not wish to be limited to the details shown and described herein but intend to cover all such changes and modifications as are obvious to one of ordinary skill in the art.

We claim:

1. In a radio receiver having a power source, a gain controllable intermediate frequency amplifying circuit for operatively amplifying an intermediate frequency signal containing an audio frequency signal to be detected, a signal detection circuit connected to the output of said intermediate frequency amplifying circuit and including at least a detection diode, a resistor and a capacitor connected together in parallel, and an intermediate frequency transformer having a secondary winding connected in series with said diode across said parallel circuit of said resistor and said capacitor and a primary winding connected to the output of said intermediate frequency amplifying circuit, so that the audio frequency signal is separated from the intermediate frequency signal and appears across said parallel circuit, a time constant circuit including at least a potentiometer having an adjustable terminal and a time constant resistor connected in series with said signal detection circuit to said power source so

that the audio frequency signal appearing across the parallel circuit inversely varies the potential at the junction between said potentiometer and said time constant resistor, and a time constant capacitor connected to said junction to provide a time constant, so that an automatic gain control voltage variable in response to the amplitude of the audio frequency signal thus separated is obtained across said time constant capacitor, said junction being connected to the input of said amplifying circuit, the amplification factor of which is inversely controlled by application thereto of the automatic gain control voltage, so that its output is successively transferred to said detection circuit, and an audio frequency amplifying circuit connected to said detection circuit for amplifying the audio frequency signal output of the detection circuit, an improved squelch circuit comprising: a squelch transistor; a biasing circuit including connecting means for connecting the adjustable terminal of said potentiometer to the base of said squelch transistor for providing between the base and emitter of said squelch transistor a bias voltage, which bias voltage is so determined by adjustment of said potentiometer that the conductivity state of the squelch transistor is provided only during a non-signal input condition of the receiver; and means for varying the bias voltage of the audio frequency amplifying circuit in response to change in the conductivity state of the squelch transistor so that the audio frequency amplifying circuit is conducting only when an audio frequency signal is detected by the detection circuit.

2. The combination defined in claim 1, wherein the emitter of said squelch transistor is connected to said power source along with said parallel circuit so that the bias voltage on said squelch transistor is variable with changes in the audio frequency signal across said parallel circuit.

3. The combination defined in claim 2, wherein said means for varying the bias voltage of said audio frequency amplifying circuit includes a bias resistor in said audio frequency amplifying circuit connected to the collector of said squelch transistor for cutting-off said audio frequency amplifying circuit when said squelch transistor is conductive.

4. The combination defined in claim 3, wherein said audio frequency amplifying circuit includes an audio amplifying transistor having an emitter connected to said bias resistor and a base connected to a voltage divider circuit which is connected to said power source, said voltage divider circuit providing a bias to said base which is larger than said emitter bias when said squelch transistor is non-conductive and is smaller than said emitter bias when said squelch transistor is conductive.

5. In a radio receiver including

a power source,
a gain controllable intermediate frequency amplifying circuit for operantly amplifying an intermediate frequency signal containing an audio frequency signal to be detected,
a signal detection circuit including at least a diode, a resistor and a capacitor connected together in parallel, and an intermediate frequency transformer having a primary winding connected to the

output of said intermediate frequency amplifying circuit and a secondary winding connected in series with said diode across the parallel circuit of said resistor and said capacitor, so that an output signal is obtained across said parallel circuit,

an automatic gain control circuit including a time constant resistor, a time constant capacitor, and a potentiometer having an adjustable terminal, said time constant resistor and said potentiometer being connected in series with said parallel circuit across said power source, said time constant capacitor being connected at one end thereof to a junction between said time constant resistor and said potentiometer and at the other one end thereof to one polarity terminal of said power source, said power source being directed in such a manner that it normally biases said diode forwardly, and

an audio frequency amplifying circuit for amplifying the output signal of said signal detection circuit, an improved squelch circuit comprising:

a squelch transistor having emitter, base and collector, the emitter-collector circuit being connected across said power source;

bias means for biasing said squelch transistor to the conductive or non-conductive side of its operating characteristic during a non-signal input or a signal input condition of the receiver, respectively, said biasing means including connecting means for connecting the adjustable terminal of said potentiometer to the base of said squelch transistor; and means for varying the conductivity of said audio frequency amplifying circuit inversely to the change in the conductivity of said squelch transistor.

6. The combination defined in claim 5, wherein said means for varying the conductivity of said audio frequency amplifying circuit includes a bias resistor in said audio frequency amplifying circuit connected to the collector of said squelch transistor for cutting off said audio frequency amplifying circuit when said squelch transistor is conductive.

7. The combination defined in claim 6, wherein said audio frequency amplifying circuit includes an audio amplifying transistor having an emitter connected to said bias resistor and a base connected to a voltage divider circuit which is connected to said power source, said voltage divider circuit providing a bias to said base which is larger than said emitter bias when said squelch transistor is non-conductive and is smaller than said emitter bias when said squelch transistor is conductive.

8. In a radio receiver having

- a power source,
- a gain controllable intermediate frequency amplifier for operantly amplifying an intermediate frequency signal applied thereto which contains an audio frequency signal to be detected,
- a signal detector including a diode, an intermediate frequency transformer having a primary coil coupled to an output terminal of said intermediate frequency amplifier and a secondary coil connected in series to said diode, a smoothing circuit coupled to said secondary coil through said diode, so that the audio frequency

signal is separated from the intermediate frequency signal and appears across said smoothing circuit,

- d. an automatic gain control circuit including
    - a potentiometer having a movable contact and 5 connected in series with one electrode of said power source through said smoothing circuit as well as a series circuit formed by said secondary coil and said diode, and
    - a time constant circuit connected between said 10 potentiometer and the other one electrode of said power source so that said diode is normally biased forwardly by said power source and backwardly by an audio frequency signal appearing across said smoothing circuit, a junction 15 point between said potentiometer and said time constant circuit at which an automatic gain control voltage is obtained being coupled to an input terminal of said intermediate frequency amplifier, so that the gain of said intermediate frequency amplifier is controlled by the automatic gain control voltage, and
    - e. an audio frequency amplifier coupled to said signal detector for amplifying the audio frequency signal applied from said signal detector,
- an improved squelch circuit comprising:
- a squelch transistor which is operable in on and off states and operantly drives said audio frequency amplifier to off and on states, respectively;
  - first connecting means for connecting the movable 30 contact of said potentiometer to a base of said squelch transistor;
  - second connecting means for connecting an

emitter of said squelch transistor to the other electrode of said power source, so that a bias voltage is provided between the emitter and the base of said squelch transistor, said bias voltage being so determined by adjustment of a position of the movable contact of said potentiometer that the bias voltage has a value larger than a threshold voltage of said squelch transistor unless the audio frequency signal of an intensity larger than a desired intensity appears across said smoothing circuit.

9. The combination as defined in claim 8, which further includes a bias resistor for said audio frequency amplifier connected to a collector of said squelch transistor so as to allow collector current to flow therethrough to thereby operantly cut off said audio frequency amplifying circuit when said squelch transistor is conductive.

10. The combination as defined in claim 9, which further includes a bypass capacitor connected in parallel with said bias resistor and connected to the collector of said squelch transistor.

11. The combination as defined in claim 9, wherein said audio frequency amplifier includes an audio frequency signal amplifying transistor having an emitter connected to said bias resistor and a base connected to a voltage divider circuit which is connected to said power source, said voltage divider circuit providing a bias to the base of said audio frequency signal amplifying transistor which is larger than said emitter bias when said squelch transistor is conductive.
